WINDOW CONSTRUCTION

Arthur W. Grist, Newport News, Va., assignor, by
mesne assignments, to Brown & Grist Com-
pany, Newport News, Va., a copartnership
composed of Robert A. Cassidy, Robert F. Flax-
ington, Bernard J. Utley, L. E. Wooldridge, and
R. G. Brown

Application August 2, 1948, Serial No. 41,910

12 Claims. (Cl. 189—67)

1

This invention relates, as indicated, to window sash and more particularly to an awning type window structure in which a plurality of sash or ventilators are superimposed and interconnected for synchronous movement.

The various advantages of this general type of construction are being increasingly appreciated, partly as a result of the present great popularity of metal sash such as aluminum sash which is especially adapted for such use. This invention is concerned with improving certain features which have caused trouble and annoyance in the past while at the same time providing an assembly which is very simple to install and operate.

A primary object of my invention is to provide a window of the type indicated in which only one of a series of ventilators or sash is connected to the supporting frame by means of a link having fixed points of pivotal attachment, the other ventilators being "free-floating."

Another object of my invention is to provide means whereby all such ventilators will be self-locking in open position.

A further object is to so mount the individual sash or ventilators that full four-sided double sealing is obtained when closed.

Still another object is to provide one set of tie bars for controlling the vertical position of the ventilators and another set for controlling their angular position.

Other objects of my invention will appear as the description proceeds.

To the accomplishment of the foregoing and related ends, said invention then comprises the features hereinafter fully described and particularly pointed out in the claims, the following description and the annexed drawing setting forth in detail certain illustrative embodiments of the invention, these being indicative, however, of but a few of the various ways in which the principle of the invention may be employed.

In said annexed drawing:

Fig. 1 is a perspective view of a window employing the sash of my invention;

Fig. 2 is a vertical sectional view thereof showing the means whereby such sash are mounted and interconnected;

Fig. 3 is a horizontal sectional view taken along the line 3—3 on Fig. 2;

Fig. 4 is a horizontal sectional view taken along the line 4—4 on Fig. 2;

Fig. 5 is an enlarged perspective view of the lower sash of Fig. 1; and

Fig. 6 is an enlarged vertical sectional view taken through such lower sash and frame.

5 Referring now more particularly to said drawing, the window construction of my invention comprises a rectangular frame 1 into which are mounted a plurality of superimposed swinging sash 2, 3, and 4. As will appear below, the precise number of sash to be employed is a matter of choice and the proportions and dimensions thereof may be selected as desired. The top, bottom, and sides of frame 1 may desirably be formed 10 of aluminum angle members having laterally extending side flanges 5 adapted to engage the outer surface of the wall in which the window is installed. An inner frame consisting of aluminum angle members 6 is mounted within frame 1 and serves to provide a neat and pleasing appearance as viewed from within the building, concealing the sash mounting means from view. The outer edge of such inner frame 6 also serves the additional purpose of providing an inner seal 15 for the sash when the latter are closed.

20 Frame 1 is divided into vertically arranged sections by means of crossbars 7 and 8, each such bar carrying an outwardly protruding downturned lip or flange 9 and 10 respectively. A similar lip 11 is provided on the upper cross member of frame 1. These lips or flanges serve to receive the outer upper edge of the respective sash to provide a weather seal when the latter are in closed position.

25 The three sash proper are themselves identical although the respective mounting means therefore differ somewhat as explained below. Each sash is rectangular and may be formed of aluminum angle members of Z cross-section having laterally outwardly extending flanges 12, and peripheral inwardly extending flanges 13 connected by an intermediate web or wall portion 14. The sash will be glazed in the usual fashion with the glass 15 set in putty 16. The upper transverse portion of flange 12 is adapted to fit snugly under the corresponding downturned lip such as 10 carried by crossbar 8 (Figs 2 and 5) and at the sides and bottom of the sash such flange engages and overlies laterally extending flange 5 of main frame 1. Inner peripheral flange 13 is adapted to engage the edge of inner frame 6 and at the top of the sash to engage downturned flange 17 of the crossbars such as crossbar 8. It will thus be seen that a double weather seal is obtained about the entire circumference of each sash. It will be appreciated that the foregoing description of the sash, while referring principally to the lower sash member 4, is nevertheless equally applicable to the other two sash members 2 and 3.

30 55 As best shown in Figs. 2 and 6, lower sash mem-

ber 4 is provided with link members 18 and 19 pivotally connected to frame 1 at 20 and to the side of the sash at 21. Only the lower sash is provided with such links.

A pair of lever arms 22 and 23 are also provided pivoted to the respective sides of frame 1 at a fixed point 24. The outer ends of such lever arms carry slide followers 25 fitting in slides 26 on the outer sides of the sash. When the sash are in closed position, slide followers 25 will be in the lower end of slide 26 (Fig. 2) and, when the sash are in open position, such slide followers will be in the upper end of the slide (Fig. 6). Lever arms 22 have offset portions 27 beyond fulcrum pivots 24 and vertically extending connecting rods 28 pivotally connect the ends of such offset portions 27 of each respective tier of lever arms, thereby insuring that all will move in synchronism about their pivots 24.

The upper ends of the respective sash are retained within frame 1 during outward swinging movement of the sash by means of slide brackets 29 pivotally secured to side webs 14 of the sash at 30 and traveling in generally vertically extending slideways 31. As best shown in Fig. 6, slideways 31 incline slightly inwardly at their upper ends so that as the upper edge of the sash descends it will simultaneously move slightly outwardly. When the sash is returned to closed position, this movement will be reversed while the sash swings about its pivot 30 into vertical position. Thus, as indicated above and with reference to Fig. 2, it will be understood that because slideways 31 incline slightly inwardly at their upper ends, the upper portion of the sash is caused to shift bodily inwardly relative to the frame during final closing movement of the sash compensating for the simultaneous outward swinging movement of flange 12 about pivot 30 whereby such flange may be inserted behind depending lip 10 to bear against the outer face of the upper transverse window portion thus to facilitate the obtaining of a tight weather seal without danger of jamming. As best shown in Fig. 6, pivot 30 projects above the upper edge of the sash a distance substantially equal to the upward extent of sash flange 12 so that during final closing movement for example, the outward swinging movement of the flange is relatively small requiring only slight inclination of the guideway to offset such swinging movement. Although such arrangement of the pivot with respect to flange 12 is not absolutely necessary, nevertheless, in most instances the same will ordinarily be preferred in order that the amount of inclination of the slideways may be kept small. It will be understood of course that the slideways need be inclined in their upper regions only thus to facilitate obtaining a tight seal. However, in the interests of economy, such slideways will ordinarily be straight and uniformly inclined as shown. Brackets 29 of the respective tiers of sash are rigidly connected by means of bars or rods 32 so that the upper edges of the respective sash are required to move in synchronism.

It will now be apparent that when the lower sash 4 is opened to the position shown in Figs. 1, 5, and 6, the upper sash are caused to follow suit and will at all times be exactly parallel with lower sash 4. The pair of links 18 and 19 secured to such lower sash, however, are all that are required to lock the entire set in open position. When it is desired to again close the window, the upper edge of the lower sash may be grasped and manually elevated whereupon all of the sash will swing

closed with a minimum of effort. A lock or catch 33 will ordinarily be provided for the lower sash only to secure them all in such closed position.

Other modes of applying the principle of the invention may be employed, change being made as regards the details described, provided the features stated in any of the following claims or the equivalent of such be employed.

I therefore particularly point out and distinctly claim as my invention:

1. In an awning type window structure having a plurality of superimposed sash mounted in a frame for outward swinging movement, generally vertical slideways in the sides of such frame, there being a pair of said slideways for each sash, slides adapted to travel in each of said slideways with the upper portions of such respective sash pivotally secured thereto, connecting rods interconnecting said slides of each vertical tier to cause the same to move in unison, crossbars dividing the window opening of such frame into vertically arranged sections corresponding to each such sash, outwardly protruding downturned flanges on each said crossbar and the upper cross member of such frame forming weather seals of inverted, generally U-shaped conformation, peripherally laterally outwardly extending flanges on each such sash adapted to tightly engage such frame in closed position and in their upper transverse portions to fit snugly into such weather seals, thereby providing an external seal, said slideways sloping slightly outwardly in a downward direction, whereby, during final closing movement of such sash, such upper portions of such sash are caused to shift bodily inwardly relative to such frame compensating for the simultaneous outward swinging movement of such upper transverse portions of said flanges about such points of pivotal connection and facilitating insertion of such upper transverse portions into such weather seals, slideways on the outer sides of each sash, lever arms pivotally mounted on the sides of such frame and carrying slides at their outer ends fitted in and adapted to travel along said latter respective slideways, offset portions of said lever arms beyond such fulcrum pivots, vertically extending connecting rods pivotally interconnecting the respective ends of said offset portions of each vertical tier to cause said lever arms to swing in unison to maintain the respective sash in parallel planes, a pair of links for such lowermost sash only pivotally secured at one end to such frame and at the other end to a side of such sash to hold the same in open position, an inner frame within said first frame enclosing and concealing said arms, links, and rods when such sash are in closed position and adapted to engage such sash to provide a further internal seal, and means adapted to lock said lowermost sash in closed position.

2. In an awning type window structure having a plurality of superimposed sash mounted in a frame for outward swinging movement, generally vertical slideways in the sides of such frame, there being a pair of said slideways for each sash, slides adapted to travel in each of said slideways with the upper portions of such respective sash pivotally secured thereto, connecting rods interconnecting said slides of each vertical tier to cause the same to move in unison, slideways on the outer sides of each sash, lever arms pivotally mounted on the sides of such frame and carrying slides at their outer ends fitted in and adapted to travel along said latter respective slideways, offset portions of said lever arms be-

yond such fulcrum pivots, vertically extending connecting rods pivotally interconnecting the respective ends of said offset portions of each vertical tier to cause said lever arms to swing in unison to maintain the respective sash in parallel planes, and a pair of links for such lowermost sash only pivotally secured at one end to such frame and at the other end to a side of such sash to hold the same in open position.

3. In an awning type window structure having a plurality of superimposed sash mounted in a frame for outward swinging movement, means mounting the upper portions of such sash for vertical sliding movement and outward swinging movement, means interconnecting such sash adapted to synchronize such vertical movement, lever arms pivotally mounted on such frame, each said arm having an end pivotably and slidably secured to the side of a respective sash, means pivotally interconnecting said arms for movement thereof in unison, and link means pivotally secured to said frame at one end and at the other end to the lowermost of such sash only to hold the same in open position and thereby through said connecting means likewise hold such other superimposed sash in corresponding position.

4. In a window structure having a plurality of superimposed sash mounted in a frame for outward swinging movement, means mounting such respective sash for downward sliding and outward swinging movement, means interconnecting such mounting means adapted to synchronize such downward movement, lever arms pivotally mounted on such frame, each said arm having an end pivotably and slidably secured to the side of a respective sash, and means pivotally interconnecting said arms for movement thereof in unison.

5. In a window structure having a sash mounted in a frame for outward swinging movement, generally vertical slideways in the sides of such frame sloping slightly outwardly in a downward direction, slide means mounting the upper portion of such sash for pivotal and longitudinal movement with respect to said slideways, and link means pivotally secured to such frame at one end and at the other end to such sash to support the latter in open position.

6. In an awning type window structure having a plurality of superimposed sash mounted in a frame for outward swinging movement, means mounted in such frame for generally vertical sliding movement with the upper portions of such respective sash pivotally secured thereto, means interconnecting the aforesaid means to cause the latter to move in unison, slideways on the outer sides of each sash, lever arms pivotally mounted on the sides of such frame and carrying slides at their outer ends fitted in and adapted to travel along said respective slideways, offset portions of said lever arms beyond such fulcrum pivots, vertically extending connecting rods pivotally interconnecting the respective ends of said offset portions of each vertical tier to cause said lever arms to swing in unison to maintain the respective sash in parallel planes, and a pair of links for such lowermost sash only pivotally secured at one end to such frame and at the other end to a side of such sash to hold the same in open position.

7. In an awning type window structure having a plurality of superimposed sash mounted in a frame for outward swinging movement, means mounted on such frame for generally vertical sliding movement with the upper portions of such respective sash pivotally secured thereto, means interconnecting the aforesaid means to cause the

latter to move in unison, slideways on the outer sides of each sash, lever arms on the sides of such frame and carrying slides at their outer ends fitted in and adapted to travel along said respective slideways, means pivotally interconnecting said arms for movement thereof in unison to maintain the respective sash in parallel planes, and link means pivotally secured to said frame at one end and at the other end to one of such sash only to hold the same in open position and thereby through said interconnecting means likewise hold such other sash in corresponding position.

8. In an awning type window structure having a plurality of superimposed sash mounted in a frame for outward swinging movement, means mounting such sash for vertical sliding and outward swinging movement, means interconnecting such sash adapted to synchronize such vertical movement, slideways on the outer sides of each sash, lever arms pivotally mounted on the sides of such frame and carrying slides at their outer ends fitted in and adapted to travel along said respective slideways, offset portions of said lever arms beyond such fulcrum pivots, vertically extending connecting rods pivotally interconnecting the respective ends of said offset portions of each vertical tier to cause said lever arms to swing in unison to maintain the respective sash in parallel planes, and link means pivotally secured at one end to such frame and at the other end to one of such sash only to hold the same in open position.

9. In a window structure having a sash mounted in a frame, means mounting said sash for downward sliding movement of the upper portion thereof and simultaneous outward swinging movement of the lower portion thereof comprising generally vertical guideways on said frame, and means mounting the upper portion of said sash for pivotal movement with respect to said guideways and movement lengthwise thereof; an upwardly extending transverse flange on the upper edge of said sash adapted to overlap and lie closely adjacent to the outer face of the upper transverse portion of said frame when said sash is closed, said guideways sloping slightly outwardly in a downward direction at least in the upper portions thereof, whereby, during final closing movement of said sash, such upper portion of said sash is caused to shift bodily inwardly relatively to said frame compensating for the simultaneous outward swinging movement of said flange about such point of pivotal connection.

10. In a window structure having a sash mounted in a frame, means mounting said sash for downward sliding movement of the upper portion thereof and simultaneous outward swinging movement of the lower portion thereof comprising generally vertical guideways on said frame, and means mounting the upper portion of said sash for pivotal movement with respect to said guideways and movement lengthwise thereof; a transverse downwardly projecting flange on said frame above the window opening, and an upwardly extending transverse flange on the upper edge of said sash adapted to overlap and lie closely adjacent to the outer face of said flange on said frame when said sash is closed, such point of pivotal connection being located above such upper edge of said sash a distance substantially equal to the upward extent of said flange thereon, and said guideways sloping slightly outwardly in a downward direction, whereby, during final closing movement of said

sash, such upper portion of said sash is caused to shift bodily inwardly relative to said frame compensating for the simultaneous outward swinging movement of said flange on said sash about such point of pivotal connection.

11. In a window structure having a sash mounted in a frame, means mounting said sash for downward sliding movement of the upper portion thereof and simultaneous outward swinging movement of the lower portion thereof comprising generally vertical guideways on said frame, and means mounting the upper portion of said sash for pivotal movement with respect to said guideways and movement lengthwise thereof; a transverse, inverted channel on said frame above the window opening, and an upwardly extending transverse flange on the upper edge of said sash adapted to fit closely within said channel when said sash is closed to provide a weather seal, such upper portion of said sash is caused to shift bodily inwardly relative to said frame compensating for the simultaneous outward swinging movement of said flange on said sash about such point of pivotal connection and facilitating insertion of said flange into said channel.

12. In a window structure having a sash mounted in a frame, means mounting said sash for downward sliding movement of the upper portion thereof and simultaneous outward swinging movement of the lower portion thereof comprising generally vertical guideways on said frame, and means mounting the upper portion 35

of said sash for pivotal movement with respect to said guideways and movement lengthwise thereof; a transverse, inverted channel on said frame above the window opening, and an upwardly extending transverse flange on the upper edge of said sash adapted to fit closely within said channel when said sash is closed to provide a weather seal, such point of pivotal connection being located above such upper edge of said sash a distance substantially equal to the upward extent of said flange thereon, and said guideways sloping slightly outwardly in a downward direction, whereby, during final closing movement of said sash, such upper portion of said sash is caused to shift bodily inwardly relative to said frame compensating for the simultaneous outward swinging movement of said flange on said sash about such point of pivotal connection and facilitating insertion of said flange into said channel.

ARTHUR W. GRIST.
